UNITED STATES PATENT OFFICE.

ALFRED R. HODGE, OF CHICAGO, ILLINOIS.

DESIGN FOR A PORTABLE EXTERIOR FRONT OF AN AMUSEMENT BOOTH OR BUILDING.

52,741.

Specification for Design.

Patented Dec. 10, 1918.

Application filed July 13, 1917. Serial No. 180,457. Term of patent 3½ years.

To all whom it may concern:

Be it known that I, ALFRED R. HODGE, a citizen of the United States, residing at Chicago, in the county of Cook and State of Illinois, have invented a new, original, and ornamental Design for a Portable Exterior Front of an Amusement Booth or Building, of which the following is a specification, reference being had to the accompanying drawing, forming a part thereof.

The figure is a front elevation of an

amusement building front showing my new design.

I claim:

The ornamental design for a portable exterior front of an amusement booth or building as herein illustrated.

ALFRED R. HODGE.
